D10-60. OR D 16,845 EX

No. 16,845.

UNITED STATES PATENT OFFICE.

FRIEDRICH OERTLING, OF BERLIN, GERMANY.

DESIGN FOR A BAROMETER-FRAME.

SPECIFICATION forming part of Design No. 16,845, dated August 10, 1886.

Application filed June 7, 1886. Serial No. 264,426. Term of patent 7 years.

To all whom it may concern:

Be it known that I, FRIEDRICH OERTLING, of the city of Berlin, in the Empire of Germany, have invented and produced a new and 5 original Design for a Barometer-Frame, of which the following is a specification, reference being had to the accompanying photograph, forming a part thereof.

The design consists of a circular plate or 10 frame ornamented by a series of mythological illustrations arranged in the space between its edge and an inner circle; also in a series of pictorial illustrations grouped within said inner circle, as hereinafter described.

15 In the accompanying drawings, Figure 1 is a face view of the entire barometer frame, and Fig. 2 is a face view of the portion inclosed by the inner circle.

The details of the design are as follows: 20 The circular frame or plate A has the inner circle, a. In the annular space between the latter and the edge of the frame is arranged a series of oval figures or illustrations, l m n o, taken from Grecian mythology. The same are 25 placed equidistant. The figure l represents Phœbus Apollo, the god of the sun, in his chariot. m represents Jupiter on his throne, amidst clouds, with Boreas, the god of the wind, on his left. n represents Luna in her 30 chariot, and o represents Neptune mounted on an equine riding the sea. These several ornamental illustrations constitute the chief

or most striking and important feature of the design. The other series of illustrations is arranged within the inner circle, a, and are 35 arc-shaped to adapt them to the annular space b between the latter and the barometer proper. The central one, d, of these arc-shaped pictures represents a landscape, and a man, woman, and boy walking. The figures on the 40 right of said central one, d, are respectively as follows: The first, e, is a rural scene, with lady and child in foreground. The second, f, is an Egyptian landscape, including a camel and a pyramid. The third, g, is an architectural ruin, such as is produced by earthquakes. 45 On the left of the central figure, d, the figures are as follows: the first, h, shows a ship at sea in a storm, the next one, i, is a light-house, and the last, k, an architectural ruin. 50

What I claim is—

1. The design for a barometer frame herein shown and described, the same consisting of figures l m n o, arranged in the annular space between the inner edge and inner circle of the 55 frame.

2. The design for a barometer-frame herein shown and described, the same consisting of the mythological figures l m n o and the arc-shaped figures e, arranged in the space b.

FRIEDRICH OERTLING.
